Attorney's

UNITED STATES PATENT OFFICE.

FRED ADRIEN BRONCHAIN, OF McDONALD, PENNSYLVANIA.

WRENCH.

No. 906,192.

Specification of Letters Patent.

Patented Dec. 8, 1908.

Application filed June 4, 1908. Serial No. 436,729.

To all whom it may concern:

Be it known that I, FRED A. BRONCHAIN, a citizen of the United States, residing at McDonald, in the county of Washington, State of Pennsylvania, have invented certain new and useful Improvements in Wrenches; and I do hereby declare the following to be a full, clear, and exact description of the invention, such as will enable others skilled in the art to which it appertains to make and use the same.

This invention relates to wrenches, more particularly to the class known as quick action wrenches or those in which the movable jaw may be adjusted in one direction, and has for one of its objects to simplify and improve the construction and increase the efficiency and utility of the implement.

Another object of the invention is to provide a simply constructed wrench wherein the parts may be readily disconnected for the renewal or repairs of any parts which may be broken or impaired.

With these and other objects in view the invention consists in a wrench comprising a stock having a stationary jaw at one end and with spaced ratchet teeth transversely in one of its faces, a movable jaw slideable over the stock and with an internal recess and a transverse aperture communicating with the recess, a pawl having ratchet teeth and movable bodily with the recess and provided with a stud extending therethrough and slidably engaging the aperture, said stud having an elongated slot next to the body of the pawl and with an aperture near the outer end, the aperture designed to receive a pull ring and the slot designed to support a spring operating to maintain the pull yieldably in engagement with the teeth of the stock.

The invention further consists in certain novel features of construction as hereafter shown and described and specifically pointed out in the claims, and in the drawings illustrative of the preferred embodiment of the invention, Figure 1 is a side elevation of the improved wrench. Fig. 2 is an edge view of the same. Fig. 3 is a side elevation with the movable jaw in section. Fig. 4 is a perspective view of the pawl detached.

The improved device comprises a stock 10 having a stationary jaw 11 at one end and with ratchet teeth 12 transversely of one of its faces, preferably one of the edge faces of the stock. The teeth 12 are formed in about

one-half of the length of the stock and the remainder of the stock comprises a portion of the hand grip, this portion having spaced apertures 13-14 to receive clamp bolts 15-16 whereby hand grips 17-18 are secured to the side faces of the stock, the stock and the members 17-18 thus forming an efficient handle or grip to the wrench.

Slidably disposed over the toothed portion of the stock is a movable jaw 19 provided with an elongated internal recess 20 and with a transverse aperture 21 communicating with the recess, the aperture located beneath the overhanging portion 22 of the movable jaw. Fitting in the recess 20 and movable bodily therein is a pawl 23 having teeth 24 corresponding to and adapted to engage the teeth 12 of the stock. The pawl 23 is provided with a lateral stud 25, the latter 75 provided with a slot 26 adjacent to the body of the pawl and with an aperture 27 near its outer end, the aperture coming outside of the body of the jaw 19 and adapted to receive a pull ring 28. The rear face of the pawl 23 is also provided with small recesses 29-30 near its ends, and fitting through the slot 26 is a spring 31 with its ends bearing in the recesses 29-30. The spring thus exerts its force to maintain the teeth 24 of the pawl 23 yieldably in engagement with the teeth of the stock, while the pull ring 28 enables the operator to release the pawl when it is desired to adjust the movable jaw.

The teeth 12 of the stock and the teeth 24 of the pawl have one side inclined or oblique to the longitudinal plane of the stock, so that the movable jaw may be adjusted toward the stationary jaw without manipulating the jaw as the teeth 24 simply click 95 over the teeth 12 when the movable jaw is adjusted in one direction but effectually hold it from movement in the opposite direction and when the movable jaw is to be adjusted away from the stationary jaw the pawl is 100 released by pulling upon the ring 28 and holding the pawl disconnected from the stock during the adjustment of the movable jaw, and when the desired adjustment is reached the pawl ring is released when the spring 31 105 will immediately connect the pawl to the stock.

The means whereby the spring 31 is supported in position is an important feature of the invention and operates effectually for 110 the purpose required, and being so very simple will not be liable to get out of order or

become disarranged. In event of the break-
age of the spring a new one may be readily
supplied by detaching the hand grip mem-
bers 17-18 and removing the jaw 19 from
the stock, and the pawl may be readily de-
tached by removing the pull ring 28, when
a new spring can be attached and the pawl
again inserted into its cavity 30 and the
pull ring restored. The movable jaw can
then be replaced upon the stock and the
hand grip members 17-18 restored.

The device is simple in construction, can
be inexpensively manufactured and of any
desired strength and of any desired material,
and may also be manufactured in various
sizes.

What is claimed, is:—

1. A wrench comprising a stock having
spaced teeth in one face and with a sta-
tionary jaw at one end, hand grip members
20 detachably engaging the opposite sides of
the stock, an opposing jaw slidably engag-
ing the stock and formed with an internal
cavity and with a transverse aperture com-
municating with the cavity, a pawl movable
bodily within said cavity and with teeth
in one edge engaging the teeth of the stock,
said pawl having a stud projecting through
said aperture and formed with a transverse
30 slot next to the body of the pawl and an

aperture exteriorly of the jaw, a spring
bearing through said slot and against the
bottom surface of the recess and with its
terminals engaging the pawl, and means op-
erating upon said stud to withdraw said 35
pawl from engagement with the stock.

2. A wrench comprising a stock having
spaced teeth in one face and with a sta-
tionary jaw at one end, a opposing jaw
40 slidably engaging the stock and formed with
an internal cavity and with a transverse
aperture communicating with the cavity, a
pawl engaging said cavity and movable
bodily therein and with teeth at one edge
corresponding to the teeth of the stock and 45
adapted to engage the same, said pawl hav-
ing a stud projecting through said aperture
and provided with a transverse slot next the
body of the pawl and an aperture exteriorly
of the jaw, a spring operating through said 50
slot and bearing between the pawl and the
body of the movable jaw, and a pull ring
detachably engaging said stud externally of
the movable jaw.

In testimony whereof, I affix my signa- 55
ture, in presence of two witnesses.

FRED ADRIEN BRONCHAIN.
